C. B. FORWARD.

APPARATUS ADAPTED TO DISTILL CRUDE PETROLEUM.
FILED JUNE 13, 1917.

UNITED STATES PATENT OFFICE.

CHAUNCEY B. FORWARD, OF URBANA, OHIO.

APPARATUS ADAPTED TO DISTILL CRUDE PETROLEUM.

Application filed June 13, 1917. Serial No. 174,457.

To all whom it may concern:

Be it known that I, CHAUNCEY B. FORWARD, citizen of the United States, residing at Urbana, in the county of Champaign and State of Ohio, have invented certain new and useful Improvements in an Apparatus Adapted to Distill Crude Petroleum, of which the following is a specification.

My invention relates to an apparatus for producing a powerful motor fuel oil from crude petroleum according to the mode of operation set forth in my application for Letters Patent filed March 16, 1917, Serial Number 165,595.

In the accompanying drawings, Fig. 1 is a sectional diagrammatic elevation of the apparatus as an entirety and with the several operating parts coupled up in working relations and substantially faithful in detail to the actual structure. Fig. 2 is a longitudinal sectional elevation of one of the oil pre-heating units and which is referred to herein as the secondary heater or preheater in contradistinction to the primary or lower heater shown in Fig. 1, a portion being broken out at the middle. Fig. 3 is an end elevation of Fig. 2 with the head of the cylinder removed to disclose the oil conducting coils therein.

My invention comprises a suitable steam boiler, say such as herein shown having drums 2 and connecting tubes 3, and a superheater therewith comprising a main or primary coil 4 and a secondary or auxiliary coil 5. The live steam leaves the boiler by pipe 9 and flows first to superheating coil 4 and thence to coil 5 by pipe 6, and the said secondary superheater or coil 5 is purposely placed in the heat flue of the boiler where it will receive the most direct heat generated therein, and the steam is discharged from coil 5 by pipe 10 into two connected oil preheaters. By these means I can maintain a constant steam pressure of 100 to 300 pounds or higher in the boiler, and superheat the steam up to a temperature of 500° Fahrenheit, or higher, preparatory to entering the oil preheaters.

The said oil preheaters comprise continuous coils of pipe 13 and 15, each having a suitable enclosing cylinder or chamber 12 and 14, respectively, and the coils extend the full length of said cylinders or chambers substantially as shown. The coils are of great length but compactly housed by this arrangement, and the oil flows through the

coils in a continuous stream and is heated to a very high temperature without danger of coking or other deleterious effect, because the flow of the superheated steam through the preheaters is inverse to the flow of the oil. Thus, the steam flows first into the secondary heater 12, where the temperature of the oil has been gradually raised to take advantage of this condition, and the entrance of the steam into cylinder 12 is by valved pipe 16 and the two discharge nipples 17 at opposite ends of the cylinder. Thence the steam passes by short pipe or passage 18 into the primary preheater or cylinder 14, heating the coil 15 and the oil flowing therethrough on its way to coil 13. In this way the cold oil is first subjected to the steam at a lower temperature in cylinder 14 and then to the steam at a higher temperature in cylinder 12.

Finally, the steam is discharged from cylinder 14 by the pipe 20 and a portion thereof used to operate the oil pump 21, while the balance passes off through pipe 22 to be used for any and all purposes for which steam is used about the plant. Pump 21 has a suitable pipe connection 23 with the oil supply tank or source 24 to feed the oil by a pipe 25 into primary coil 15, and which connects by elbow 26 with coil 13.

When the heated oil passes from the secondary preheater by way of pipe 30 into the separator or still 27, it is exposed to highly-heated steam entering through an injector 32 connected with a pipe 33 leading to the main steam supply pipe 10, and the hydro-carbons volatile at that high temperature are converted into vapor without having subjected the oil to sudden contact with highly-heated metal containers. The residuum deposited in separator 27 is discharged under valve control through a pipe 35, while the volatile hydrocarbons are discharged through the baffle column 36 and connecting pipe 37 to the condenser 38, thus practically completing the operation.

Using this apparatus, both the motor fuel and the residuum are in better condition for all purposes than when separated or distilled by direct heat as is commonly used, and the specific gravity or end point by distillation of the motor fuel oil may be made higher or lower as desired according to the temperatures maintained in the preheaters and still, which can be varied at will by the operator.

What I claim is:

1. An apparatus for treating hydro-carbon oils, comprising a plural number of openly-connected cylinders adapted to hold 5 separate large bodies of steam, means adapted to discharge a large volume of super-heated steam into said cylinders continuously and successively, separate coils of pipe of great length compactly housed within 10 each of said cylinders and successively connected with each other and adapted to convey an attenuated stream of oil back and forth for great distances through the separate bodies of steam within each cylinder, 15 means adapted to force a stream of oil continuously through said coils of pipe, a closed vapor and liquid separating vessel, a discharge connection for the heated oil leading from said coils of pipe into said vessel, 20 separate discharge connections for the volatilized and liquid separations within said vessel, and means adapted to effect a continuous outflow of the volatilized and liquid separations through said separate 25 discharge connections while maintaining a constant pressure within said vessel.
2. An apparatus for treating hydro-carbon oils, comprising an oil pump, separate sets of compact coils of pipe of great length connected in series with said pump and each 30 other, separate enclosing cylinders for said coils of pipe having open communication with each other and providing separate large steam chambers, means adapted to deliver a continuous supply of superheated 35 steam to said cylinders inversely to the flow of oil through said pipe, a closed vapor and liquid separating vessel, means adapted to deliver the heated oil from said coils of pipe together with steam into said vessel, 40 separate vapor and liquid discharge connections for said vessel, means in each of said discharge connections adapted to control pressure conditions within said vessel under the force of the steam and oil discharged 45 thereinto, and a condenser connected with the vapor discharge connection.

Signed at Cleveland, in the county of Cuyahoga, and State of Ohio, this 8th day of June, 1917.

CHAUNCEY B. FORWARD.
